CLAIM

The ornamental design for a card with an ornamental rectangle, machine readable stripe and IC chip, as shown.

DESCRIPTION

FIG. 1 is a perspective view of a card with an ornamental rectangle, machine readable stripe and integrated circuit (IC) chip, showing my new design;
FIG. 2 is a front view of the card of FIG. 1;
FIG. 3 is a rear view of the card of FIG. 1;
FIG. 4 is a front elevational view thereof; and,
FIG. 5 is a right side elevational view thereof.
